BUCKET CHAIR

William J. Harris, New York, N.Y., assignor to The General Fireproofing Company, Youngstown, Ohio, a corporation of Ohio

Filed Mar. 30, 1962, Ser. No. 69,510

Term of patent 14 years

(Cl. D15—1)

FIG. 2.

FIG. 1.

FIG. 3.

FIG. 4.

The side of the chair not shown in FIGURE 4 is the same in appearance as the side shown.

I claim:

The ornamental design for a bucket chair, as shown and described.
